Attorney.

UNITED STATES PATENT OFFICE.

LOUIS PRINCE, OF WASHINGTON, DISTRICT OF COLUMBIA.

BRICK-MOLD AND BRICK.

SPECIFICATION forming part of Letters Patent No. 278,268, dated May 22, 1883.

Application filed November 8, 1882. (No model.)

To all whom it may concern:

Be it known that I, LOUIS PRINCE, a citizen of the United States, residing at Washington, in the District of Columbia, have invented certain new and useful Improvements in Brick-Molds and Bricks; and I do hereby declare the following to be a full, clear, and exact description of the invention, such as will enable others skilled in the art to which it appertains to make and use the same.

My invention relates to improvements in brick-molds and bricks; and the object is to produce a brick-mold in which the bricks are not liable to stick, as is now usually the case, and at the same time to form a brick having a tapering perforation through it, so that in forming walls a clear passage for air is left from bottom to top, thus preventing frost from penetrating through the wall, and forming a non-conducting wall against heat, cold, dampness, &c., while at the same time producing a much lighter wall.

The invention consists in the construction and arrangement of parts, as will be more fully described hereinafter, and specifically pointed out in the claims, reference being had to the accompanying drawings and the letters of reference marked thereon.

Like letters of reference indicate like parts in the different figures of the drawings, in which—

Figure 1 represents a top view of the mold. Fig. 2 is a longitudinal section on line *xx*. Fig. 3 is a cross-section of a modification. Fig. 4 is a plan view of one of the bricks. Fig. 5 shows several bricks laid together. Fig. 6 is a view of the covering or top brick. Fig. 7 is a similar brick for the corners. Fig. 8 is a vertical section of part of a wall. Fig. 9 is a view of a gage used in laying the bricks.

In the accompanying drawings, *A* represents the frame of the mold, having cross-pieces *a*, to which two straps or bars, *B*, of metal or other material are secured and extending from end to end. The side pieces are preferably bound with sheet metal to strengthen them.

To the longitudinal bars are secured backs *b* of the molds—in this instance six being shown, although more or less may be used.

The backs of the molds are beveled off on their sides and ends and do not quite fill the mold-space, but leave a narrow opening, *c*, on all

sides. The object of this is to break the vacuum when the molds are filled with clay and permit the access of air, by which the bricks will be forced out of the molds and the adhesion to them is prevented. This is a very important feature of my invention, as it is well known in the state of the art that many bricks are lost or spoiled by the clay adhering to the molds, and it is desired to empty them for removal to the kiln, &c. The mold-backs are provided with tapering pieces *d*, which form the perforations *e* in the bricks *C*, and, if desired, a semicircular hole, *f*, may be made in the ends of the bricks.

As a modification of the molds shown in Figs. 1 and 2, the backs *b* may be secured in place by two pins, *g*, on each side, which extend into the ends or sides of the mold-back. Suitable washers, *h*, are then placed over the pins to form the proper width of opening *e*, as shown in Fig. 3, between the back and the sides.

In constructing a wall it will be readily seen that a continuous passage or opening is formed when the bricks are laid, and the finishing or top course, which is formed of bricks *D*, having a concave depression, *i*, and at the corners similar bricks, *E*, are placed, having a solid end, which is provided with small perforations *k*, so that the wind passing through them can create a constant circulation of air, created by the draft through the upper row of bricks. Whenever it is desired to cross the bricks or form ties of them they are laid as shown in Fig. 5, and will always form a continuous opening through the entire wall. It will be readily understood that the size of the opening can be varied as desired, it merely being of the proper size that the adjoining bricks with their openings communicate, and thus form a continuous passage for the air.

In laying the bricks a gage or strip of the form shown at *F*, Fig. 9, is placed over the openings *e* at the narrow ends and of the thickness of the mortar, to prevent it entering into said openings.

The great advantages of my improved construction of brick-molds, as well as bricks, will be readily appreciated by those skilled in the art, and among some of them may be mentioned, that the bricks or clay will not adhere to the molds, but will readily leave them without the

loss caused by breakage, &c.; the saving in material and cost of digging and manipulating the clay will be greatly reduced; in drying a large amount of time will be saved, as also in burning them; the expense in hauling and transportation, as well as handling, will be greatly reduced; the weight of the wall will be about two thirds of a wall built of solid brick, and is, therefore, much lighter; and with all this a wall will be produced that will resist heat, cold, dampness, &c., much better, and will obviate the "furring out" required in a solid wall. The expense will of course be greatly reduced.

I reserve to myself the right to make a separate application for the bricks shown in Figs. 6 and 7, and claim it therein, as I make no claim to the same in this application.

Having thus described my invention, what I claim, and desire to secure by Letters Patent, is—

1. A brick-mold consisting of a frame with a series of partitions and the permanent backs, forming narrow openings *e*, as and for the purpose herein set forth.

2. A brick-mold consisting of a frame with a series of partitions and permanent backs constructed to form openings *e*, and provided with tapering pieces *d*, substantially as specified.

3. A brick-mold consisting of a frame, *A*, provided with a series of partitions, *a*, to which the straps *B* are secured, in combination with a series of backs, *b*, forming annular openings *c*, substantially as shown, and for the purpose described.

4. As a new article of manufacture, a brick, *C*, provided with a tapering hole, *e*, substantially as shown and specified.

5. A wall consisting of hollow bricks *C*, having tapering hole *e*, in combination with covering-bricks *D* and *E*, the latter provided with solid ends and perforations *k*, all arranged substantially as shown and specified.

In testimony whereof I hereby affix my signature in presence of two witnesses.

LOUIS PRINCE.
